BOTTLE CAP

Vincent Guarnaschelli, New York, N. Y., assignor
to Self Seal Bottle Cap Company, Long Island
City, N. Y., a copartnership

Application October 21, 1943, Serial No. 507,061

2 Claims. (Cl. 215—38)

The invention relates to bottle caps particularly caps which may lend themselves to reuse upon removal from a bottle containing beverage or the like.

The object of my invention is to provide a novel, simple sealing cap for bottles that may be readily applied to the open neck of a bottle and hermetically seal the broached receptacle for the preservation of the contents of the bottle that may remain after the bottle has been first opened and a portion of liquid therein removed.

Referring to the accompanying drawing forming a part of this specification:

Fig. 1 is a side view of a bottle neck and of my improved sealing cap mounted thereon.

Fig. 2 is a transverse sectional view of the improved sealing cap.

Fig. 3 is a bottom plan view of my cap.

Fig. 4 is a perspective view of the improved sealing cap and exposing its novel construction.

The improved sealing cap is preferably made of non-corrodible metal such as aluminum and may with advantage be stamped out of flat resilient stock material or be cast in form from suitable material.

The device consists of an imperforate disk 10 rounded on a periphery, and having a peripheral flange 10a that projects below the flat inner surface thereof sufficiently to form a shallow recess wherein is embedded a flat circularly edged planchet 11 of cork or other slightly yielding material. The flange 10b is cut out at the front to provide an entrance mouth S for the cap. The top central portion is preferably indented or cupped inwardly at 10' to provide yield of the flange portion. Integrally with the flange 10a the flanged extension 10b is formed and it has an inwardly projecting lip 105 upon the lower edge thereof; the lip is provided with three suitably located spaced apart inwardly projecting extensions 101, 102, 103 as appears in Figs. 3 and 4. The lip extensions 101, 102, 103 are arcuate and of a greater radius of curvature than the flange 10b. Upon the upper surfaces of the lip 105 and the extensions 101, 102, 103, upwardly extending rounded cam-like projections 106, 107, and 108, are formed. The peaks of these projections occur substantially above the midpoints of their respective lip extensions and the troughs between the projections occur above the junctions of adjacent lip extensions, as is apparent in Fig. 4.

The improvement is designed to be mounted upon a class of bottles used for packing aerated or other beverages or the like. Usually these

bottles have similar necks 12 at their pouring ends, each terminating in a radial bead 12a as shown in Fig. 1.

The lips, or lip extensions, 101, 102 are spaced apart at the shoulders of the cut-out S on the extension 10b a distance that permits them to be slid under the bead 12a at opposite points thereon. This is effected by first imposing the joint planchet 11 upon the edge of the bottle neck 12 opposite the cut-out S and then pressing the cap piece 10 home in the direction of the arrow in Fig. 1. The arcuately rising projections 106, 107 will thus frictionally engage the underside of the bead. The arcuately rising formation of the projections 106, 107 facilitates the grip of the cap on the bead, and cooperative with the rear projection 108 and with the resiliency of the planchet and of the cap an effective seal is provided. The similarly arcuately rising projection 108 at the rear prevents tilt of the cap and limits its slide movement. The rear projection 108 moreover performs the additional function of facilitating loosening of the cap and initiating its movement in a rearward direction upon the application of the thumb or finger against the underside of the flange 10b at the rear, or of a bottle cap removing tool in the same manner, as will be described below.

It will be seen that the sliding engagement of the cap piece as hereinbefore described, will compress the elastic joint planchet 11 upon the true top edge of the bottle neck 12 and thus seal the same hermetically holding the gaseous liquid contents therein until the bottle is broached by the removal of the cap piece.

Another method of fastening the cap upon the bead 12a may be employed such as placing the cap on the edge of the bottle neck centrally relative to the axial line of the bottle, and pressing it downwardly to spread the resilient lip extensions 101, 102, 103 and their upward projections 106, 107, and 108 over the bead to resiliently grasp the underside of the bead.

The cap may be removed with or without the aid of a cap removing tool. In either case, the lower rear edge of the flange 10b is pried or forced upward, thereby causing simultaneous rearward movement of the cap for a short distance owing to the sliding of the rear projection 108 on the bead 12a. With the rearward loosening movement of the cap thus initiated (and obviously with the application of a very small amount of force), complete removal of the cap by sliding it rearward is greatly facilitated.

The description is intended to be illustrative rather than limitative.

I claim:

1. A bottle cap for a bottle having an annular bead at its mouth, comprising a member adapted to cover the mouth of the bottle having a depending peripheral flange extending from the peripheral edge thereof, said flange having a cut-out at the front of the cap of a size which is adapted to receive said bead, the lower peripheral edge of said flange lying in a plane parallel with the peripheral edge of said member, said flange having an inwardly projecting lip along the lower edge thereof, said lip having circumferentially spaced upwardly extending rounded cam-like projections on the upper surface thereof on the sides of said flange and having an additional upwardly projecting rounded cam-like projection at the rear of said flange, said projections being

adapted to engage the underside of said bead to clamp said cap on said mouth.

2. A bottle cap for a bottle having an annular bead at its mouth, comprising a member adapted to cover the mouth of the bottle having a depending peripheral flange extending from the peripheral edge thereof, said flange having a cut-out at the front of the cap of a size which is adapted to receive said bead, the lower peripheral edge of said flange lying in a plane parallel with the peripheral edge of said member, said flange having an inwardly projecting lip along the lower edge thereof, said lip having circumferentially spaced upwardly extending rounded cam-like projections on the upper surface thereof on the sides of said flange, said projections being adapted to engage the underside of said bead to clasp said cap on said mouth.

VINCENT GUARNASCHELLI.
